CLAIM

The ornamental design for a plumbing fixture handle, as shown and described.

DESCRIPTION

FIG. 1 is a perspective view taken from the top, front and right side of a plumbing fixture handle showing my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a bottom plan view thereof; and

FIG. 7 is a rear elevational view thereof.

The fragmentary broken line representations of a toilet tank wall in FIG. 1 and of a stem toilet trip lever control in FIGS. 2 and 4-6 are for purposes of illustration only.
